(57) **CLAIM**

The ornamental design for a garment for converting into a backpack, as shown and described.

DESCRIPTION

FIG. 1 illustrates a perspective view of a design for a garment for converting into a backpack, in its garment configuration;

FIG. 2 illustrates a rear view thereof;

FIG. 3 illustrates a front view thereof;

FIG. 4 illustrates a left side elevation view thereof;

FIG. 5 illustrates a cut-away section view taken along line 5-5 of FIG. 2;

FIG. 6 illustrates a right side elevation view thereof;

FIG. 7 illustrates a top plan view thereof;

FIG. 8 illustrates a bottom plan view thereof; and,

FIG. 9 illustrates a perspective view of the design for the garment for converting into a backpack, in its backpack configuration.

The dashed broken lines shown in the drawings illustrate environment only that forms no part of the claim.
